J. S. THOMPSON

BRAKE SHOE MOLD

Filed July 20, 1923

Inventor:
James S. Thompson
By: Wm. O. Bell Atty.

UNITED STATES PATENT OFFICE.

JAMES S. THOMPSON, OF PELHAM, NEW YORK.

BRAKE-SHOE MOLD.

Application filed July 20, 1923. Serial No. 652,773.

To all whom it may concern:

Be it known that I, JAMES S. THOMPSON, a citizen of the United States, residing at Pelham, in the county of Westchester and State of New York, have invented certain new and useful Improvements in Brake-Shoe Molds, of which the following is a specification.

This invention relates to the manufacture of brake shoes, and its object is broadly to facilitate the manufacture of brake shoes in permanent molds by providing a mold in which the parts to be embedded in the shoe casting can be easily inserted and supported in position and which can be readily and quickly opened and closed so that the casting operation may be speedily and economically performed.

Another object of the invention is to provide a permanent mold of simple construction adapted for the reception of the attaching lug, the core for forming the opening in the lug and the reinforcing back, which can be conveniently inserted and easily supported in the mold cavity preliminary to closing the mold for the casting operation.

In the accompanying drawing I have illustrated a selected embodiment of the invention, and referring thereto—

Fig. 1 is a central sectional view on the line 1—1 of Fig. 2.

Fig. 2 shows the mold of Fig. 1 partly in elevation and partly in longitudinal section.

Fig. 3 is a horizontal sectional view on the line 3—3 of Fig. 2.

Referring to the drawings, the mold comprises a drag member 6 and a cope comprising a relatively fixed member 7 and a slidable member 8. The drag is hinged at 9 to the fixed member 7 of the cope and is adapted to swing freely down from the cope as indicated in broken lines in Fig. 1. The cope member 8 is provided with ears 10 bored to receive the guide bars 11 mounted on the fixed member 7 of the cope, and projecting forward to support the member 8 of the cope in its sliding movement to and from closed position with relation to the other members of the mold. The drag member has one or more tongues 12 which are adapted to be secured in slotted keepers 13 by removable pins 14 to hold the drag in closed position against the cope. One or more clamping bars 15 is pivotally

secured to the fixed member 7 of the cope at 16 and carries a set screw 17 at its free end to engage the slidable member of the cope for holding the slidable member in proper relation to the fixed member of the cope during the casting operation. When the mold is closed, the two members of the cope will be held rigidly clamped together and the drag member will be held rigid in its proper relation to the cope.

The parting line between the two members of the cope extends longitudinally of the mold and substantially central of the mold cavity 18 which is formed, in the construction illustrated, almost entirely in the cope. A part of the mold cavity is located in one cope member and a part in the other cope member, and there is also an opening 19 of substantial size extending through the cope and communicating with the mold cavity. A sand plug 20 preferably carried by a holder 21 fits snugly in the opening 19 and it is provided with a recess 22 to form the attaching lug of the shoe casting.

In practice, the mold having been opened to discharge a casting, the slidable cope member 8 is pushed into closed relation with the fixed cope member 7 and the clamp 15 applied to secure them together. Then the plug 20, with suspending wires 23 therein, is inserted in the opening 19 in the cope, the ends of the wires projecting well down into the mold cavity and suitably spaced apart. The attaching lug 24, the core 25 for forming the opening in said lug and the reinforcing back 26 are then inserted in the mold cavity through the bottom thereof, assembled as a unit, and when properly positioned in the mold cavity the ends of the wires 23 are twisted together beneath the reinforcing back to hold this assembled back unit in position for the casting operation. The wires are spaced apart on opposite sides of the attaching lug and they are preferably spread by a support 27 extending across the top of the plug so that the legs will project in parallel relation down through the plug on opposite sides of the reinforcing back, and when the ends of the wires are twisted together the entire back unit will be held snugly and securely in place in the mold cavity.

I have shown a broad support 27 to effect the spreading of the wires, but it will be understood that very little support is required

to hold the wires in place, and while this broad support seems to be desirable for the purpose, the results desired can also be accomplished by other means, such as one or more comparatively light rods or bars. I prefer to provide the plug with a projection 28 to engage the top of the lug 24, as shown in Fig. 1, and to form an abutment against which the back unit is clamped, in effect, by the wire ties, but this is not essential to the practice of my invention, because the end portions of the back bear against the top of the mold cavity, which, under all ordinary conditions, will be sufficient to prevent disarrangement of the back unit during the casting operation. By providing the projection 28 to engage the top of the lug 24, the cast metal is prevented from flowing over the lug, and hence the lug will be bare in the finished casting, where the projection has engaged with the lug.

I have illustrated my present invention in a mold adapted for casting integral composite brake shoes having chilled ends and an intermediate soft cast iron wearing face. The chilling of the shoe casting is effected by direct contact with the metal of the mold, and to prevent this chilling effect from extending throughout the shoe I provide refractory sections in the walls of the mold. The refractory section 29 in the drag and the refractory sections 30 in the cope prevent the metal of the drag and cope from having a chilling effect upon the shoe casting opposite thereto while the bare portions of the walls of the mold cavity, at the ends thereof, permit the shoe casting to be chilled in the manner and to the extent desired. I may provide the refractory material as sections inserted in the drag and cope, or as a sectional coating applied to the drag and cope.

After the back unit has been secured in place in the mold cavity the drag member of the mold is swung upward to closed position with the tongue engaging the slotted keeper and the pin 14 is inserted in the keeper to hold the drag member in place. Then the mold is ready for the pouring operation and the cope is provided with a pouring gate 31 conveniently disposed.

My invention provides a permanent mold of simple and convenient form whereby brake shoes can be manufactured with facility, as good and better in quality than in sand molds, and more economically. The sand core provides for the escape of gases and after the casting is made it can be broken down to facilitate the discharge of the shoe casting if, for any reason, the casting does not drop out of the mold of its own weight when the mold is open. It will be observed that when the drag member is permitted to swing down to open position and the sliding member of the cope is moved to

open position the shoe casting may be readily discharged from the fixed member of the cope without injury to any of the parts of the mold. By providing for the entire drag member to swing downward free from the cope to leave the entire mold cavity open at the bottom I greatly facilitate the operation of inserting and tying the attaching lug, the core therefor and the reinforcing back, and these can be easily assembled and properly positioned in the mold cavity and secured in that position by tying the wires with comparatively little skill or effort.

If the wires are not destroyed in the casting operation, they can be easily removed from the shoe casting by chiseling or otherwise.

I have illustrated the invention in a selected embodiment which I believe will be readily understood by those skilled in the art, but I do not wish to be restricted to the use of my invention for the manufacture of this particular type of brake shoe since it can be used with satisfactory results in the production of other brake shoes, and other castings, and I consider myself entitled to make all such changes in the form, construction and arrangement of parts as fairly fall within the scope of the following claims.

I claim:

1. A permanent mold for making castings, comprising a drag and a cope having a mold cavity therein, said cope having an opening communicating with said cavity, a sand plug in said opening, the drag member being movable bodily away from the cope to leave the bottom of the mold cavity open so that parts to be embedded in the casting may be inserted in the mold cavity through the bottom thereof, means carried by said plug for suspending said parts in the mold cavity, and means for securing the members of the mold in closed position during the casting operation.

2. A permanent mold for making castings, comprising a drag member and a two-member cope having a mold cavity therein, one member of the cope being fixed and the other member being slideable, said cope having an opening formed partly in one member and partly in the other member and communicating with said cavity, a sand plug in said opening, the drag member being movable bodily away from the cope members to leave the bottom of the mold cavity open so that parts to be embedded in the casting may be inserted in the mold cavity, and means for securing the members of the mold in closed position during the casting operation.

3. A permanent mold for making castings, comprising a drag and a cope having a mold cavity therein, said cope having an opening communicating with said cavity, a sand plug seated in said opening and re-

- cessed to form a part of the mold cavity for the accommodation of the attaching lug, said drag being movable bodily away from the cope to leave the bottom of the mold cavity open so that parts to be embedded in the casting may be inserted in the mold cavity through the bottom thereof, means carried by said plug for suspending said parts in the mold cavity, and means for 10 curing the members of the mold in closed position during the casting operation.
4. A permanent mold for making castings, comprising a drag member and a two-member cope having a mold cavity therein, 15 said cope having an opening communicating with said cavity and one member of the cope being fixed and the other member being slidible, the drag member being hinged to the fixed cope member to swing freely 20 away from the bottom of the cope and leave the cavity open at the bottom to permit the insertion of the parts to be embedded in the casting, a sand plug seated in said opening in the cope, and means extending through 25 said plug and into the mold cavity to be engaged with said parts for suspending the parts in the mold cavity preliminary to closing the mold and during the casting operation.
- 30 5. A permanent mold for making castings, comprising a drag member and a two-member cope having a mold cavity therein, said cope having an opening communicating with said cavity and one member of the 35 cope being fixed and the other member being slidible, the drag member being hinged to the fixed cope member to swing freely 40 away from the bottom of the cope and leave the cavity open at the bottom to permit the insertion of the parts to be embedded in the casting, a sand plug seated in said opening in the cope, and means for suspending the parts in the mold cavity preliminary to closing the mold and during the casting operation.
6. A permanent mold for making castings, comprising a drag and a cope having a mold cavity therein, said cope having an opening communicating with said cavity and the drag member being movable away from the cope to leave the cavity open at the bottom to permit the insertion of the parts to be embedded in the casting, a sand plug seated in said opening in the cope, and looped wires embedded in the sand plug and projecting therethrough to enter the cavity for engagement with said parts to suspend the parts in the cavity preliminary to closing the mold and during the casting operation.
7. A permanent mold for making castings, comprising a drag and a cope having a mold cavity therein, said cope having an opening communicating with said cavity and the drag being movable away from the cope to leave the cavity open at the bottom to permit the insertion of the parts to be embedded in the casting, a sand plug seated in said opening in the cope, and looped wires embedded in the sand plug and having their free ends extending therethrough to enter the cavity for engagement with said parts to suspend the parts in the mold preliminary to closing the mold and during the casting operation, and a support extending across the top of the plug and engaging the looped portions of said wires to hold the wires in place.

JAMES S. THOMPSON.
